MECHANICAL TOY FIGURE

Walter L. Strauss, 1107 Broadway,
New York, N.Y. 10010

Filed Jan. 17, 1967, Ser. No. 5,454

Term of patent 7 years

(Cl. D34—4)

FIG. 1 is a front elevational view of a toy figure showing my design;

FIG. 2 is a left-hand side view of FIG. 1;

FIG. 3 is a right-hand side view of FIG. 1; and

FIG. 4 is an elevational rear view of FIG. 1.

I claim:

The ornamental design for a mechanical toy figure, as shown.
